CLAIM

The ornamental design for an album page, as shown and described.

DESCRIPTION

FIG. 1 is a perspective view of an album page, showing a first embodiment of my new design;

FIG. 2 is a front elevational view thereof;

FIG. 3 is a perspective view of an album page, showing a second embodiment of my new design; and,

FIG. 4 is a front elevational view thereof.

The broken lines shown in the figures are for the purpose of illustrating portions of the album page that form no part of the claimed design.
